Specification for Design.

Patented Sept. 23, 1913.

Application filed July 14, 1913. Serial No. 779,053. Term of patent 14 years.

To all whom it may concern:

Be it known that I, ELLSWORTH A. HAWTHORNE, a citizen of the United States, and a resident of Bridgeport, in the county of Fairfield and State of Connecticut, (whose post-office address is 35 Spruce street, Bridgeport, Connecticut,) have invented a new, original, and ornamental Design for a Lamp-Bracket, of which the following description, in connection with the accompanying drawings, is a specification.

In the drawing, the view is a perspective

of the lamp bracket having the design of my invention.

What I claim is:

The ornamental design for a lamp bracket, as shown.

In testimony whereof, I have signed my name to this specification in the presence of two subscribing witnesses.

ELLSWORTH A. HAWTHORNE.
